[57] CLAIM

The ornamental design for a paperback display rack, substantially as shown and described.

DESCRIPTION

FIG. 1 is a front elevational view of a paperback display rack showing our new design;

FIG. 2 is a top plan view thereof;

FIG. 3 is a perspective view thereof;

FIG. 4 is a front elevational view of a second embodiment of the rack shown in FIG. 1, the top view being identical to that as shown in FIG. 2;

FIG. 5 is a perspective view of the second embodiment of the rack shown in FIG. 4;

FIG. 6 is a front elevational view of a third embodiment of the rack shown in FIG. 1, the top view being identical to that shown in FIG. 2; and

FIG. 7 is a bottom plan view of FIG. 6.

*FIG. 1.**FIG. 2.**FIG. 3.**FIG. 5.*FIG. 4.

FIG. 6.

FIG. 7.
